WILLIAM S. PACA, OF OIL CITY, PENNSYLVANIA, ASSIGNOR TO THE STROMBERG-CARLSON TELEPHONE MANUFACTURING COMPANY, OF ROCHESTER, NEW YORK, A CORPORATION OF NEW YORK.

ASSOCIATED-SWITCHBOARD TELEPHONE SYSTEM.

1,353,065.

Specification of Letters Patent. Patented Sept. 14, 1920.

Application filed November 19, 1917. Serial No. 202,748.

To all whom it may concern:

Be it known that I, WILLIAM S. PACA, a citizen of the United States, residing at Oil City, in the county of Venango and State of Pennsylvania, have invented certain new and useful Improvements in Associated-Switchboard Telephone Systems, of which the following is a full, clear, and concise description.

10 It has been a common practice in operating telephone switchboards to divide up the same into sections at each of which is located a multiple jack for each of the telephone lines, and associated therewith a signal lamp to indicate a call originating on the associated telephone line.

In such switchboards of the art as have been in common use, the lamps of the different switchboards operate simultaneously upon the initiation of a call by a subscriber, and it often happens that several operators will attempt to answer the same call.

It is an object of this invention to prevent much of this confusion and to arrange the apparatus so that a first operator which I will call the "main" operator will have the first chance to answer the call, but that if before the same is answered other calls appear on her switchboard which must be attended to, that upon a given predetermined number of such calls appearing on the switchboard, controlling apparatus associated therewith will cause the signal lamps of the different lines to be displayed at the associated switchboard, and the operator at the said associated switchboard will thereupon have her attention directed toward these calls which have produced an over-load on the first or main switchboard, and will thereupon answer some of these calls thereby reducing this over-load.

Referring to the figures, in Figure 1, I show two telephones connected to telephone lines leading from substations to an exchange, consisting of two switchboards, a main and an associated switchboard. The main switchboard contains an answering jack and a signal lamp for each of the lines, the lamps being lighted in response to any call over either of the lines.

It will be understood that more than two lines would ordinarily be provided for such a switchboard, two only being shown in the embodiment illustrated.

At the associated switchboard likewise 55 jacks and signal lamps are provided for each of the lines, the lamps being arranged to operate however, only when an over-load occurs at the main switchboard. This would be caused by a predetermined number of 60 calling subscribers displaying their line signals at the main switchboard at the same time. Marginal relay apparatus is shown to control the operation of the signals at the associated switchboard in response to such 65 an over-loaded condition at the main switchboard.

Fig. 2 shows in general the same apparatus as Fig. 1, and in addition associated common controlling apparatus consisting of 70 an interrupter and circuit connections to cause this common interrupter to be associated with the signal lamps of such an over-loaded switchboard and of the signal lamps at the associated switchboard and corresponding to the main switchboard lamps, 75 the same when operated producing a "fluttering" of the lamps to indicate the over-loaded condition.

In order to better understand the invention, I will now describe the same referring to the drawings and to reference characters placed thereon to designate the different parts.

Referring to Fig. 1, we will assume that 85 the subscriber at "A" institutes a call at the main switchboard by taking his receiver from the hook, and closing the hookswitch contacts 2 at his instrument. This will cause the operation of the line relay LR at 90 the main switchboard which will close its contacts 3 and operate the signal lamp SA over the following circuit. From the ground pole of battery, through the common exchange battery, the contacts 3 of the relay 95 LR, the signal lamp SA, circuit conductor 4, circuit conductor 5 which is common to a plurality of signal lamps, the common marginal relay M, the common pilot relay P to the ground pole of battery. The pilot relay 100 P will be operated lighting the pilot lamp PL in the usual manner, but the marginal relay M will not be energized sufficiently to overcome the power of the spring S, holding its armature in normal position so that the contacts 6 in the circuit of the signal lamp SA² will not be closed, and the signal lamp SA² will not be operated to display a sig-

nal. The signal lamp SA however, will display a signal.

The operator at the main switchboard would ordinarily answer the call and extinguish the signal SA by operating the cut-off relay CR of the line circuit. However, we will assume that the operator being busy with answering other calls on lines not shown in the figure, or in conversation with 10 a subscriber on one of the said lines, does not have time to answer the signal displayed by the lamp SA, and that at this time the subscriber "B" takes his receiver from the hook to make a call and closes his hook- 15 switch contacts 7, thus operating his line relay LR. This relay being operated, contacts 8 thereof will be closed completing a circuit from the ground pole of battery, the common exchange battery, the contacts 8 of 20 the relay LR, the signal lamp SB, circuit conductor 9, the common circuit conductor 5, the common marginal relay M, the common pilot relay P to the ground pole of battery. The current flowing over this circuit reinforcing the current flow over the same through the signal lamp SA will cause 25 the electromagnet of the marginal relay M to be energized to such a degree that it will attract its armature overpowering the spring 30 S, and closing the contacts 6 leading to the signal lamps SA² and SB² at the associated switchboard. The closing of the contacts 6 will complete a circuit to operate these signal lamps from the ground pole of battery 35 through the contacts 6, the circuit conductor 10 which is common to all of the lamps on the associated switchboard which are extensions of the lamps on the particular main switchboard having the marginal relay M, 40 and from thence the circuit is divided, the path to battery including several branches; one of which includes the signal lamp SA² and the other the signal lamp SB², from circuit conductors 11 and 12 leading through 45 relay contacts 23 and 28 to the negative pole of battery.

Thus the calls originating from substations A and B and normally indicated by the lighting of signal lamps SA and SB at the 50 main switchboard are extended to the associated switchboard by the lighting of the signal lamps SA² and SB², whose operative circuits have just been described. This occurs only when a predetermined number of 55 lamps are lighted at the same time at a main switchboard thereby causing a sufficient current to flow through the marginal relay M thereat. These calls may therefore be answered at either switchboard, and when 60 enough of the calls have been answered to reduce the number remaining to a predetermined number, which may be one or more than one, the marginal relay will again be released opening the circuits of the lamps at 65 the associated switchboard; and the calls

will be only indicated at the main switchboard.

Now, referring to Fig. 2, which shows the same switchboard apparatus and arrangement of lamps and associated jacks as Fig. 70 1, at N is shown a marginal relay whose winding is included in circuit with the common return conductor of the signal lamps associated with a given group of lines and located on both switchboards. This marginal relay will be operated when a given number of lamps are lighted on the two switchboards in response to a predetermined number of calls which are unanswered on the main switchboard at the same time. 75 When this occurs the armature of the relay N will be attracted closing the contacts 12, and connecting at the point 13 an intermittent shunt for all of the lamps at the two switchboards through the resistance coil 80 R and the interrupter I to the negative pole of battery.

The circuit just described is placed in multiple with the circuit leading through the lamps to the negative pole of battery, and as 90 long as the armature of the marginal relay N is attracted, therefore the interrupter I will intermittently shunt the lamps on the two switchboards causing them to flash in a characteristic manner. The flashing of 95 these lamps will notify the operators at the two switchboards that the predetermined number of calls remaining unanswered at the main switchboard has been exceeded, and notifying the associated switchboard operator that it is her duty to assist the main switchboard operator in the answering of 100 these calls. When the number of unanswered calls has been reduced to the predetermined number, the marginal relay N will break 105 contacts 12 in releasing its armature and the lamps will glow in a steady manner as before.

I wish it to be understood that many and numerous departures will suggest themselves to those skilled in the art to which this invention appertains, and I do not wish to be therefore limited to the precise embodiments described therein, but what I claim as my invention and wish to obtain Letters Patent for, is defined in the following claims: 115

1. In a telephone system, the combination with a plurality of telephone lines leading by their limbs from substations to an exchange, and subscriber operated substation calling apparatus for each of the said lines, 120 of a plurality of signals individual to each of the lines, a plurality of switchboard sections at the exchange, one of the said signals of each of the lines being located in the same switchboard section, a different switchboard section, means responsive to the actuation of the telephone calling apparatus of a calling line to operate its said first signal, and controlling mechanism automatically responsive to the operation of 125 130

more than a given number of line signals located at the said first-named switchboard section, for operating another signal for each calling line at said second switchboard section.

5. In a telephone system, the combination with a plurality of telephone lines, a main switchboard and an associated switchboard, of sets of signal lamps at the main switchboard and the associated switchboard, one lamp of each set being located at each switchboard, each of the said sets of signals being individual to a particular telephone line, and marginal controlling apparatus responsive to the number of signal lamps operated at the main switchboard to control the operation of the signal lamps at the associated switchboard.

3. In a telephone system, the combination with a plurality of telephone lines normally terminating in multiple jacks at a main exchange switchboard, a main and an auxiliary section for the said switchboard, one of the said multiple jacks being located at 25 each switchboard section, of a signal lamp individual to each of said multiple jacks, and marginal controlling means common to a plurality of the said lines at the one of the said sections to control the operation of 30 the signal lamps at another of the said switchboard sections.

4. In a telephone system, the combination with a main switchboard and an associated switchboard, of telephone lines terminating at each switchboard in multiple connection switches, of individual signal lamps at each switchboard for each of the said connection switches, substation apparatus for each of the said lines to cause the operation of 40 the said signal lamps, and common marginal controlling means responsive to the total number of signal lamps operated at any given time to change the character of the signal given by all of the said lamps 45 for each line.

5. In a telephone system, the combination of a telephone switchboard with divided sections, of a plurality of telephone lines terminating at each of the sections in multiple jacks, of signals individual to each of the lines associated with the said jacks, and common controlling mechanism responsive to the number of signal lamps at one time operated to vary the character of their 55 operation.

6. In a telephone system, the combination with a telephone switchboard divided into sections, each section containing multiple lamps and multiple jacks for a group of 60 telephone lines, call initiating apparatus on each of the telephone lines, the said call initiating apparatus operating apparatus individual to its line to cause the display of the associated call signal at one of the 65 switchboard sections, and a marginal relay,

responsive to a given flow of current therethrough, in circuit with a group of the said signal lamps at the said switchboard section, to cause the simultaneous operation of a plurality of associated switchboard lamps 70 at another switchboard section.

7. In a telephone system, the combination with a plurality of telephone lines, of a substation instrument for each line, line signals for each line under the control of its 75 substation instrument, a signal for each line being located in each switchboard section, and means responsive to the operation of more than a predetermined number of the said signals at the said switchboard section 80 to operate the other signals of the calling lines at the other switchboard sections.

8. In a telephone system, the combination with a plurality of telephone lines therefor, the said lines being divided into groups, of 85 signals individual to each of the lines, and means responsive to the actuation of more than a predetermined number of said signals of a group with which a calling line is located to control the actuation of the signal of the said calling line.

9. In a telephone system, the combination with a plurality of telephone lines leading by their limbs from substations to an exchange, and subscriber operated substation 95 calling apparatus for each of the said lines, of a plurality of signals individual to each of the lines, a plurality of switchboard sections at the main exchange, one of the said signals of each of the lines being located in 100 the same switchboard section, a different switchboard section, means responsive to the actuation of the telephone calling apparatus of a calling line to operate its said first signal, and controlling mechanism automatically responsive to the operation of more than a given number of line signals at the said first-named switchboard section for varying the indicating signals for each calling line at said second switchboard section. 110

10. In a telephone system, the combination with a plurality of telephone lines, a main switchboard and an associated switchboard, of sets of signal lamps at the main switchboard and the associated switchboard, one lamp of each set being located at each switchboard, each of the said sets of signals being individual to a particular telephone line, and marginal controlling apparatus responsive to the number of signal lamps operated at the main switchboard to vary the character of operation of the signal lamps at the associated switchboard. 115

11. In a telephone system, the combination with a plurality of telephone lines normally terminating in multiple jacks at a main exchange switchboard, a main and an auxiliary section for the said switchboard, one of the said multiple jacks being located at each switchboard section, of a signal 125

lamp individual to each of said multiple jacks, and marginal controlling means common to a plurality of the said lines at the one of the said sections to vary the character of operation of the signal lamps at another of the said switchboard sections.

12. In a telephone system, the combination with a main switchboard and an associated switchboard, of telephone lines terminating at each switchboard in multiple connection switches, of individual signal lamps at each switchboard for each of the said connection switches, substation apparatus for each of the said lines to cause the operation of the said signal lamps, and common marginal controlling means responsive to the total number of signal lamps operated at any given time to vary the signal lamps operated to indicate calling lines.

20 13. In a telephone system, the combination with a plurality of telephone lines, of a line relay for each of the lines, substation apparatus controlling the said line relay, a signal under the control of each line relay, and a common mechanism under the control of the line relays of a group of lines for altering the character of signal given by the said line signals.

30 14. In a telephone system, the combination with a plurality of telephone lines, of a line relay for each of the lines, substation apparatus controlling the said line relay, a signal under the control of each line relay, and a common mechanism under the control

of the line relays of a group of lines for 35 altering additional signals for each of the said lines, said additional signals being under the joint control of the said line relay and the said common mechanism.

15. In a telephone system, the combination with a group of telephone lines, of line signals for each of the lines, line relays for operating the said line signals, substation apparatus for operating the said line relays, common mechanism under the control of the 45 said line relays, additional signals for each of the lines, and means responsive to the actuation of the said common mechanism under the control of a predetermined number of operated line relays to vary the character of signal given by the said line signals. 50

16. In a telephone system, the combination with a group of telephone lines, of line signals for each of the lines, line relays for operating the said line signals, substation 55 apparatus for operating the said line relays, common mechanism under the control of the said line relays, additional signals for each of the lines, and means responsive to the actuation of more than a predetermined 60 number of the said relays for controlling the said mechanism, the said associated signals being under the control of the said mechanism.

In witness whereof, I hereunto subscribe 65 my name this fifth day of November, A. D. 1917.

WILLIAM S. PACA.
